[57] CLAIM

The ornamental design for a bulk storage dispensing bin and support assembly, as shown and described.

DESCRIPTION

FIG. 1 is a front elevational view of a bulk storage dispensing bin and support assembly showing my new design;

FIG. 2 is a right side elevational view thereof, the left side elevational view being a mirror image of that shown;

FIG. 3 is a rear elevational view thereof;

FIG. 4 is a top plan view thereof; and

FIG. 5 is a bottom plan view thereof.
